UNITED STATES PATENT OFFICE.

THOMAS C. LACKLAND, OF NORFOLK, VIRGINIA.

TOY GUN.

1,189,974.

Specification of Letters Patent.

Patented July 4, 1916.

Application filed August 31, 1915. Serial No. 48,288.

To all whom it may concern:

Be it known that I, THOMAS C. LACKLAND, a citizen of the United States, residing at Norfolk, in the county of Norfolk and State of Virginia, have invented new and useful Improvements in Toy Guns, of which the following is a specification.

This invention relates to improvements in toy guns, more especially toy cannons, one object of the invention being to provide an improved toy gun which in appearance resembles a large siege gun, is arranged at an angle, and which is adapted for throwing a projectile by means of compressed air and with a loud popping report.

Another object is to provide an improved toy gun of this character in which the air is compressed by a plunger in the breech of the gun and pivotally connected to a fixed point and by a rearwardly longitudinal movement of the gun which causes the plunger to move relatively forward in the gun, compress the air behind the projectile and also at the same time elevate the gun so that the projectile is thrown upwardly.

The invention consists in the construction, combination and arrangement of devices hereinafter described and claimed.

In the accompanying drawings:—Figure 1 is a side elevation of a toy cannon constructed in accordance with my invention, showing the same in initial position and with the plunger raised and disconnected from the gun in vertical lines and in lowered position for entering the breech of the gun in dotted lines. Fig. 2 is a vertical longitudinal central sectional view of the same with the plunger in the breech of the gun and arranged for compressing air behind the projectile. Fig. 3 is a plan of the same. Fig. 4 is a vertical longitudinal central sectional view of the same with the gun in its rear position and in the act of discharging the projectile. Fig. 5 is a detail transverse sectional view on the plane indicated by the line 5—5 of Fig. 3.

In the embodiment of my invention I provide a base frame 1 which may be of the form here shown or of any other suitable form, and which preferably resembles the chassis of a large modern siege gun. A longitudinal opening 2 is provided in the frame which extends nearly from end to end thereof and the side bars or members 3, which form opposite sides of said opening, form guide elements and are here shown as pro-

vided in their opposing sides with guide grooves 4. A pair of spaced lugs 5 project upwardly from the rear end of the frame 1 and are arranged near the center thereof. 60

The carriage 6 for the gun 7 comprises a base 8, a pair of cheek pieces or standards 9 which rise upwardly from the base and an arch 10 which connects the upper ends of the cheek pieces and extends over and across 65 the gun, the trunnions 11 of the gun being mounted in suitable bearing openings 12 with which the cheek pieces are provided. The base of the carriage is provided on opposite sides with guide tongues 13 which 70 operate in the guiding grooves 4 of the base frame which causes the carriage, together with the gun which is pivotally mounted therein to be moved longitudinally back and forth on the base frame. 75

The bore 14 of the gun extends from the breech to the muzzle. A plunger 15, for compressing air, is adapted to enter the bore from the breech and is provided with a rod 16 which is mounted on the pin 17 which is 80 secured in openings in the lugs 5. This pivoting pin has a head 18 at one end and is provided near the opposite end with a washer 19 and a locking pin 20. By first removing the locking pin the pivoting pin 85 can be removed to enable the plunger to be detached from the base frame if desired.

The projectile 21 is preferably made of rubber but may be made of any other suitable material and is adapted to fit tightly 90 in the bore and to be placed in the bore from the breech. The bore tapers slightly toward the muzzle and the gun is provided on its upper side, at a suitable distance from the breech with a threaded opening in which a 95 tubular mouth piece 22 is screwed. A counter-sink 23 is formed in the wall of the gun around the inner end of the tubular mouth piece and the latter is provided with an inwardly opening valve 24 which is normally held in closed position against the inner end of the mouth piece by a suitable spring 25 as shown in Fig. 4. A pair of handles 26 are provided on opposite sides of the gun near the breech and in practice 100 resemble the operating wheels of the breech block operating mechanism on siege guns.

To operate the gun a projectile is first placed in the breech of the bore and the plunger is also placed in the breech and the 110 gun moved rearwardly a sufficient distance to cause the plunger to force the projectile

forwardly a sufficient distance in the bore, and the gun is then drawn forwardly to arrange the plunger in the breech and form an air chamber in the bore between the projectile and the plunger as shown in Fig. 2. Air is compressed in the bore between the plunger and the projectile by blowing into the bore through the tubular mouth piece and is held in compressed condition in the bore by the valve 24. To fire the gun the same is then grasped by the handles 26 and moved rearwardly, thereby causing the plunger to move relatively forward in the bore and further compress the air therein so that the highly compressed air ejects the projectile with considerable force and with a loud popping report. The rearward movement of the gun in thus discharging the projectile causes the plunger, owing to its pivotal connection with the base frame, to elevate the muzzle of the gun so that the projectile is discharged upwardly and is caused to reach a considerable elevation before it falls.

25 While I have herein shown and described a preferred form of my invention I would have it understood that changes may be made in the form, proportion and construction of the several parts without departing from the spirit of the invention and within the scope of the appended claims.

Having thus described my invention I claim:

1. In a toy comprising a gun, movable on its mount, and an ejector secured to said mount and extending into the breech end of said gun whereby upon movement of the gun the projectile will be ejected.

2. In a toy comprising a gun slidably arranged upon its mount, and an ejector secured to said mount and extending into the breech end of said gun whereby upon movement of the gun the projectile will be ejected.

45 3. In a toy comprising a gun slidably arranged upon its mount, and an ejector secured to said mount rearwardly of said gun and extending into the breech end thereof whereby upon rearward movement of the gun the projectile will be ejected.

4. In a toy comprising a gun slidably arranged upon its mount, and an ejector pivotally secured to said mount rearwardly of said gun and extending into the breech end of said gun whereby upon movement of the gun the projectile will be ejected.

5. In a toy comprising a gun slidably arranged upon its mount, and an ejector mounted for movement toward or away from said mount and adapted to extend into

the breech end of said gun when in active position.

6. In a toy comprising a gun slidably arranged upon its mount, a check valve mounted in said gun whereby air will be admitted to the bore rearwardly of the projectile, and an ejector secured to said mount and extending into the breech end of said gun.

7. In a toy comprising a gun slidably arranged upon its mount and having an opening therein communicating with the bore, a check valve arranged in said opening whereby air will be admitted to the bore rearwardly of the projectile, and an ejector secured to said mount and extending into the breech end of said gun.

8. In a toy comprising a gun movable on its mount, and an ejector secured to said mount rearwardly of said gun and extending into the breech end thereof whereby upon rearward movement of the gun the projectile will be ejected and the muzzle end of the gun elevated.

9. In a toy comprising a base frame, a carriage movable thereon, a gun carried by said carriage, an ejector secured to said base frame and working within the bore of said gun whereby upon movement of the gun the projectile will be ejected.

10. In a toy comprising a base frame, a carriage movable thereon, a gun movably mounted on said carriage, an ejector secured to said base frame and working within the bore of said gun whereby upon movement of said carriage the muzzle end of said gun will be elevated and the projectile ejected.

11. In a toy comprising a gun movable upon its mount and having an opening therein and communicating with the bore, the end of the opening being counter-sunk, a check valve arranged in said opening whereby air will be admitted to the bore in the projectile and an ejector secured to said mount and extending into the breech end of said gun.

12. In a toy comprising a gun movable on its mount, the bore of said gun being tapered toward the muzzle end thereof and an ejector secured to said mount and extending into the breech end of said gun whereby upon movement of the gun the projectile will be ejected.

In testimony whereof I affix my signature in presence of two witnesses.

THOMAS C. LACKLAND.
